HOUSE OF SOLIDIFIED FOAM

Corwin D. Willson, Flint, Mich.

Application October 18, 1943, Serial No. 506,772

7 Claims. (Cl. 72—1)

1

This invention relates to space enclosure and, in particular, to a novel system of shelter construction primarily from interlockable panels of the unit-wall type having a low-density core. This invention is a continuation in part of my co-pending application Serial No. 485,642 filed May 4, 1943.

Prefabricated panels wholly from incombustible materials and of the unit-wall type: i. e., having a core with a minimum of large voids, have played a minor role to date in systems of prefabrication due to lack of precision dimensions, the lack of proper materials, the difficult joining of available materials, poor insulation and weather resistance, great weight and costly handling in large units.

As yet, insulation materials have to be largely fastened to or placed between structural members of wood and are of two types: those easily harmed by moisture, and those easily combustible. But there is no reason why the family's thermal envelope should not comprise insulation chiefly—insulation resistant to weather exposure, to fire, surface bruising, to decay, insect attack, and that itself assists in stiffening a minimal supporting structure. Space-enclosing materials having a core of extremely low density and, thus, of little strength, are awkward of use except in curtain walls and even in such walls the joining of panels of such materials is achieved either poorly or with difficulty. Before dwellings utilizing such materials may be designed to meet global needs at lower cost, it will be necessary to concentrate on the integration of the solutions of several problems simultaneously—such as: 1, the thermal resistance of the covering; 2, the moisture resistance of the covering both from outside and inside the space enclosed; 3, the resistance of the covering to fire, insects and decay; 4, the structural resistance of the covering to wrack and loading stress; 5, ease of fabricating the covering from a wide range of materials, some of which are available not too far from any global building site; 6, ease of transport of relatively large pre-finished units with a minimum of hazard; 7, ease of joining the units demountably, together with a minimum of other materials, upon the erection site.

To the extent that a solution of each of these seven problems is correlated with each of the others, invention can make simpler and cheaper what previous failure properly to integrate these problems has kept difficult and costly. Thus the primary object of this invention is the integrated

2

solution of all seven of the stated problems in a single simplified system of space enclosure.

Since panels of extremely low-density are not adapted to use as loadbearing elements, another object of the invention is the provision in a panel of the unit-wall type having a low-density core, of molded load-bearing means.

Another object of the invention is a construction unit having a core largely of inorganic low-density material bound between opposite faces largely of organic fibers having a high tensile strength.

Another object of the invention is a silicate-bound solidified plastic mass of relative low density that is highly resistant to moisture and to cracking under wrack.

These and other novel features and objects of the invention are hereinafter more fully described and claimed and the preferred form of 20 my new system of space enclosure is shown in the accompanying drawings, in which:

Fig. 1 is a rectangular plan of the space enclosed by panels of the unit-wall type and having a low-density core.

Fig. 2 is a view from the entrance side of Fig. 1 and shows the continuous lintel supporting the superstructure.

Fig. 3 is in part an enlarged vertical section taken on line 3—3 of Fig. 2 and turned ninety degrees therewith and illustrating the spacial relations of the elements of the structure—such as the footing, floor, side-wall, roof supports, roof panels, ceiling and partition panels, joining grooves and clips.

Fig. 4 is an enlarged cross-section at the joint between two typical panels, such as between those taken on line 4—4 of Fig. 2.

Fig. 5 is a more detailed cross-section of the spline shown in Fig. 4.

Fig. 6 is an enlarged cross-section of the corner column panel taken on line 6—6 of Fig. 2.

Fig. 7 is an enlarged cross-section of the flat wall panel taken on line 7—7 of Fig. 2.

Fig. 8 is an enlarged cross-section of the mid-column wall panel taken on line 8—8 of Fig. 2.

Fig. 9 is an enlarged cross-section of an alternate form of the flat wall panel shown in Fig. 7.

Fig. 10 is an enlarged cross-section of the floor panel taken on line 10—10 of Fig. 3.

The plan of the preferred system of space enclosure for the purposes stated is shown in Fig. 1, in which a continuous footing or foundation provides a ground anchorage for corner column panels 2 defining the corners of the rectangular space enclosed by flat wall panels 3 and

mid-column panels 4 and under-window panels 5, each joined interlockably and (if desired) demountably to the adjacent panel by spline 6 in a manner described hereinafter. Opening closures, such as windows 7 and door 8, are provided in the wall thus formed, the frames 9 of said closures carrying similar means (not shown) for being interlocked into the structure. As will become evident as the description proceeds, the wall formed of panels 2, 3, 4 and 5 is primarily an insulative wall of such low density as to be normally little more than a curtain wall. But in this instance columns 10 of load-bearing strength are formed as integral parts of panels 2 and 4 which are widely spaced in the wall and this wall thus becomes a wrack-resistant and bracing web between columns 10 supporting the load of the superstructure. The interior of the enclosure is provided with ceiling panels 80 and interior partitions 83. The ceiling panels 80 are connected to the partitions 83 by connecting ribs 82.

In Fig. 2, the named elements are shown in erected position and upon the ten columns 10 are supported horizontal beams comprising a continuous lintel 11 on which is imposed the load of the superstructure. If the superstructure is a floor for a second story, then the lintel 11 may comprise suitably reinforced horizontal panels of the same material as the vertical panels shown and be joined to them in the manner to be described. In this instance, the superstructure comprises a roof for the space enclosed and having panels 12 resting on purlins 13 supported by roof trusses 14 comprising upper chord 15 and lower chord 16 joined by web 17. Roof trusses 14 are positioned directly above columns 10, the lower chord of the trusses at opposite ends of the space enclosed coinciding with lintel 11. Thus, the entire load of the superstructure is carried by lintel 11 through columns 10 into the foundation 1.

In Fig. 3, lintel 11 is shown anchored to columns 10 by means of strap 18 attached to the vertical reinforcing rod 19. Clips 20, one end caught into the joint between adjacent panels in a manner to be described hereinafter, are nailed, screwed or otherwise fastened to the supporting elements of the superstructure already named. Similar clips may be used to anchor the lower ends of wall panels 2, 3, 4, and 5 to the floor panels 21 or into the floor poured as an integral slab on the ground. Water table molding 22 covers the top ends of wall panels 2, 3, and 4 and is easily removed from outside the space enclosed for placing or repairing electric cables 23, downward runs from which into outlet boxes in individual panels may be made in a manner to be described hereinafter. Fascia 24 and eaves mold 25 complete the trim between the wall and superstructure. As here utilized, elements 11, 13, 14, 15, 16, 17, 22, 24 and 25 are of wood as being best suited, cost considered, for the purpose.

Each of the wall and roof and floor panels has a longitudinally extending groove 26 in opposite edges and in Fig. 4 this groove 26 is shown as having a neck or slot 27 narrower than the groove base 28. This makes it possible, when the grooves of two contiguous panels are aligned neck to neck to enter spline 6 from the end of the groove together with cementitious sealing material 29, whereby a tensilely resistant interlock is secured between the panels that is also a seal for the joint between them. A calking compound may

be used in the seam between the panels 12 of the roof whereby the joint here being described is made resistant not only to disengagement but to leakage through it.

If spline 6 were limited to end-entrance into groove 26, this would be attended with a considerable disadvantage. Encountering the least resistance in endwise passage throughout the length of the groove, the spline, being long and slender, could not be forced easily into the locking position shown, nor could the sealing material 29 be properly distributed throughout the length of the spline. And where such a joint would be attempted in partition panels, for example, between precast floors, endwise entrance of the spline would be impossible except as an entire partition was assembled in a recumbent position. Thus provision is made for the lateral entrance of the spline 6 into groove 26.

The thickest parts 30 of the edges of the spline 6 are slightly less than the width of the slot 27. Experience demonstrates that such a spline entered into groove 26 with an excess of quick-setting cement 29 will, upon the excess being forced from the groove, be anchored with practically dovetail efficacy within the groove—if provision is made to center the spline in the groove so that the cement 29 will be well distributed between spline and groove. This is made possible by bead 31 at the waist of the spline being so proportioned as to fit closely into throat 32 exterior to neck 27 of groove 26. In Fig. 5, the spline 6 is shown reinforced to resist tensile stress by metal strip 33 having edge loops 34, the strip being covered with laminations 35, such as of fiber and asphalt given form under heat and pressure. Such a spline is resistant to the weather and other forces of disintegration.

On Fig. 6, the column part 10 of panel 2 may be precast from load-bearing material of greater density than the insulative core 36, the facing 37 or the grooved edges 38 of the panel. In many panel-built dwellings, the corners are concentrations of complexity, but here corner panel 2 is primarily a load-bearing column 10 with the wings of the curtain wall joined at a fixed and rigid angle. This permits the joints between panel 2 and 3 to be identical with the joints between the other panels and strength to be concentrated where most requisite.

Core 36 may be preformed and bonded between facing sheets 37. Or panel 3 may be integrally cast from two batches of plastic material, such as one of very low-density granular inorganic aggregate and a binder, the other of vegetable and mineral fibers and a binder, in which case facings 37 and grooved-edge portions 38 become one homogeneous surfacing mass encasing the solid core 36.

Experience has shown that core 36 may comprise expanded slate pellets weighing as little as 15 pounds per cu. ft., or may comprise the fragmented tailings trimmed from blocks of foam glass weighing as little as 10 pounds per cu. ft., the aggregate bonded with a Portland cement slurry with or without fillers between sheets of thin asbestos-cement board, the permanence of the bond assisted by an admix, such as one hereinafter described. Where core 36 is molded as shown in Fig. 7 with grooves 39 in one face, the concavities only may be coated with a superficial moisture seal, as with hot asphalt, prior to being bonded to outer facing sheets 37. Thereupon part of the back 40 of the weatherfacing 37 is exposed to part 41 of the core in cells 39. Then

in cold weather, when the inside of the dwelling shown in Fig. 2 is heated, moisture drawn into the unit wall panel from inside the dwelling by vapor pressure will tend to be sucked through the superficial moisture barrier into cells 39 and will tend to be condensed against the cold inner surface 40 and to build up there in cells 39 as frost, but during warmer weather will thaw, and will be unable to get back through the superficial moisture barrier into the core and will run down and out of the panels at outlets 42 provided through the lower outer surface of the panels. In this instance, the superficial moisture barrier acts as a valve, permitting moisture to pass outwardly under the suction of vapor pressure, but preventing its passage the other way. In consequence the condensing cells 39 act automatically to condense and carry away all moisture drawn into the cells by vapor pressure which keeps the core inwardly dry and greatly increases its insulating efficiency.

In Fig. 8, the column part 10 of panel 4 may be precast from dense aggregate reinforced with rod 19 before being included among the lighter constituents of the panel still in plastic form and experience has shown that column 10 may be so included when barely set or solidified from a plastic state. In Fig. 9 a wall panel similar to that in Fig. 7 is shown except that light core 36 and denser facings 37 and edge-portions 38 are made integral by being molded from a single mix of very light aggregate and heavier fines and vibrated while being turned so that the fines come to the surface of the panel and give it a denser "skin." In Fig. 10, floor panel 21 acquires increased thickness without excessive weight by taking the form of an inverted pan reinforced with rods 43 and mesh 44, such as of flat wire 45. In utilizing plastic materials of very low-density, flat wire increases the area of contact with the aggregate without increasing the weight of the wire.

I have found that a light, moisture-resistant and fire-retarding, insulative and bump-resistant panel that avoids the decay of its organic constituents because of the high alkalinity of the matrix and that avoids insect attack because of the slate-hard and caustic qualities of the mass, is achieved by utilizing such globally abundant and lowcost raw materials as agricultural and industrial wastes. Some of these wastes may easily be broken down to fiber-bundles possessing high tensile strength. These I have found it best to concentrate in relatively thin layers of greater density adjacent opposite surfaces of a panel, as outside line 95 in the drawings. Materials of greater particle bulk, lower cost, lesser strength and lower aircell density I concentrate in the core 36 of the panel. I have secured, defibered, stabilized and bound a very wide variety of such fiber bundles for this purpose. Among agricultural wastes which I have found useful are grain hulls—such as those from oats, cottonseed and buckwheat; stalk fibers—such as straw, flax, cornstalk and bagasse from sugar-cane; husks—as from cocoanuts; shells—as from peanuts; grass culms—such as bamboo; reeds—such as communis Phragmites, Florida sawgrass and the like that grow by the thousands of square miles in swamps and tidal waters. Not the least valuable of the available wastes are wood wastes, only a fraction of the timber cut in our forests being reduced to lumber. In the industrial extraction of various oils and juices, many fibrous materials have to be shredded and the residues

find little value except for fuel worth little more than \$3.00 per ton.

In the production of foam glass, irregular shaped blocks are trimmed to size and the tailings, having an extremely low-density when separated from denser parts, and excellent resistance to moisture absorption, are tossed onto a refuse heap unused. These tailings may be remelted and made into aircell pellets or may be ground to a size passing $\frac{1}{4}$ inch mesh screen, the denser particles separated and culled out. A residue of the slate industry is available in pellet form which has been expanded in a standard cement kiln to sizes from $\frac{1}{8}$ to $\frac{3}{8}$ inch in diameter and having an outer shell quite impervious to moisture penetration. In the fabrication of one of my typical panels, such as that in Figure 9, the core 36 may comprise largely crushed foam-glass tailings, or expanded slate pellets, or expanded mica pellets plus a small amount of the interlaced organic and inorganic fibers described above, bound with plastic Portland cement and an admix; while the facings 37 comprise a mixture largely of interlaced organic and inorganic fibers bound with plastic Portland cement and an admix. In the core the Portland cement may comprise as little as one-third by weight of the constituents; whereas in the outer facings, the fibers may comprise as little as one-third by weight of the cement.

It is not the object to go into involved detail concerning the chemical means whereby the best results in enclosing space by the means here described are achieved. What is of primary concern here is the spacial relationships of the elements. However it may be briefly explained that the admix mentioned, in one form, comprises crude alumina, such as is found in certain clays, fuller's earth, bauxite, bentonite, or in Luminite, a high-alumina cement—5 parts; a metal chloride—2 parts; a raw material containing a form of sulfur—1 part; and a solvent for one of the constituents of the admix— $\frac{1}{4}$ part or less. This admix is mixed with the wetting water so that the alumina equals $\frac{1}{2}$ (one half) to two per cent or more by weight of the Portland cement used. The purpose of the admix is to assist the normal set of the cement and to combine with the other ingredients of the matrix to form crystals of calcium sulpho-aluminate therein which, as I have explained in my co-pending application Serial No. 485,642, filed May 4, 1943, I have found to bond the fibrous materials together effectively with a minimum of Portland cement and therefore without needless weight.

The fibers used, where of organic material such as wood, may be prepared either by the "wet" or by the "dry" process. In the wet process, the wood is chipped and cooked for one to two hours in a soda ash solution before being run through a disintegrating machine, such as is manufactured by Bauer Bros. of Springfield, Ohio, for the preparation of a similar fiber from Southern pine and used in the manufacture of wallboard. In the dry process, the fibrous material is directly cut or shredded as in making excelsior and wood wool, or on such a machine as the hog manufactured by Mitts and Merrill of Saginaw, Michigan. The fineness of the fibers desired determines the process of "defiberizing" the raw wastes.

To integrate all the factors essential to obtain the stated objects of the invention, both the physical and chemical arts must be utilized. Since many fibers contain harmful solubles that tend to leach out during the mixing with the

alkali present in Portland cement and slow up or lessen the set of the cement, they may require to be "stabilized." This may be done wet by soaking them in a soda solution, as of lye, or in the chemicals commonly used to bleach vegetable fibers in the other arts. Or it may be done dry by subjecting the fibers to sunlight, heat, artificial rays or to a gas such as ozone in ways I have described in another place.

I have found that the inclusion of organic fibers in a matrix of set Portland cement, particularly where these are interlaced with inorganic fibers, produces a mass that is very resistant to cracking—the weakness of most concrete. This makes it possible to mold a relatively thin unit wall, floor or roof panel that stands up effectively because resistant to harm from freezing. Such a panel having a core impervious to moisture absorption,—such as of foam glass tailings or expanded slate pellets,—retains its insulative value.

I have found that exposure of such panels to a blowtorch flame chars the surface exposed and slowly dehydrates the water of crystallization in the bonding silicates, yet at a rate so slow as to be fire-safe and prevent active combustion. By concentrating tensilely strong fibrous material adjacent the outer surfaces of the panels, by adding stiffening means as inserts I have achieved a new and useful synthesis largely from elements old in the art, a synthesis that provides a simple solution to each of the seven basic problems, but one integrated to the one aim: a better structure at a lower cost.

Study of the previous art reveals much of apparent similarity aimed at the solution of some and even of several of these problems, but it is believed that a careful comparison between them and my new system of space enclosure demonstrates the greater simplicity and greater global adaptability of the latter in line with today's engineering imperative: Most results from least effort.

It will be understood that any of the variants and modifications in the elements essential to enclosing space in the manner described may be used separately or in any desired combination.

The drawings being illustrative only, are more or less diagrammatic in character and it is observed that various changes in the contours of the housing for the groove, for example, or in the exact form of the taper-headed spline, in forming the panels or in other phases of the invention here illustrated and described, may be made without departing from the spirit and scope of the invention as set forth in the appended claims.

Having thus fully described my invention, its utility and mode of assembly, what I claim and desire to secure by letters Patent of the United States is:

1. A building having a supporting framework and a framework-supported covering; the framework including lintel-like beams extending continuously on opposite sides of the building and roof supports widely spaced on the beams and posts fixed to the beams directly under the roof supports and a continuous foundation under the posts; the covering comprising lightweight wall-thick panels of the non-loadbearing type and having dense opposite edges spliced and continuously sealed with the contiguous edges of adjacent panels; some of the taller of the side panels extending from the foundation to one of said beams and each of said posts being an integral part of one of said taller side panels and fixed therein

midway between said opposite edges and laterally protruding from one face of the panel.

2. The structure in claim 1 wherein one of said taller panels having one of said posts integral therewith extends around one corner of the building both inside and outside thereof.

3. A building having a supporting framework and a framework-supported covering of panels, the framework including lintel-like beams extending continuously on opposite sides of the building and roof supports widely spaced on the beams and posts fixed to the beams directly under the roof supports and a continuous foundation under the posts; the covering panels being of the non-loadbearing type and having cores of siliceous solidified foam and dense opposite faces and edges sealably joined with the contiguous edges of adjacent panels; some of the taller of the side panels extending from the foundation to one of said beams and each of said posts comprising an insert in one of said taller side panels and midway between opposite edges of the panel and laterally protruding from the inside face of the panel.

25 4. The structure in claim 3 wherein said posts are of dense hard-set plastic composition and have a circular cross section.

5. A building having a supporting framework and a framework-supported covering for the top and sides and bottom of the building; the framework comprising a pair of lintel-like beams extending continuously on opposite sides of the building and a foundation extending continuously under the beams and posts fixed between the beams and the foundation; and the covering comprising an incombustible, thermally insulative and highly moisture-resistant mass of solidified siliceous foam and hard-set Portland cement reinforced with wood fiber, and said posts comprising inserts fixed in said covering and laterally protruding from the inside face thereof.

6. The structure in claim 5 wherein the binding strength of the Portland cement in the covering mass is increased by added calcium sulphoaluminate.

45 7. A building having a supporting framework and a framework supported covering; the framework comprising a pair of lintel-like beams extending continuously on opposite sides of the building and ground-support extending continuously under the beams and posts fixed between said beams and said ground support; the side covering comprising wall-thick panels of the incombustible non-loadbearing type, grooves in the dense edges of panels for fixing the panels edge-to-edge against racking and assuring sealed joints therebetween, each of said posts being an integral part of one of said panels and being fixed therein midway between opposite vertical edges of the panel and laterally protruding inwardly from the inside face of the panel.
